HERBERT GAYTES, OF OAKLAND, CALIFORNIA.

ELECTRIC ICE-CUTTER.

1,250,010.

Specification of Letters Patent. Patented Dec. 11, 1917.

Application filed March 29, 1915. Serial No. 17,691.

To all whom it may concern:

Be it known that I, GERMAIN POUCHAN, citizen of the United States, residing at the city and county of San Francisco, State of California, have invented certain new and useful Improvements in Electric Ice-Cutters, whereof the following is a specification.

This invention relates to apparatus for cutting ice or dissecting it, so to speak, that is, reducing it to the shape of small blocks, ordinarily cubical, suitable for use in restaurants.

In carrying out this invention, I cause the ice and one or more sets of wires, which are heated by electricity, to be kept in contact and thus the wires melt their way through the ice. By using a suitable number of sets of such wires the ice may be cut in as many planes as is desirable; for example, in cutting it into cubes it must be cut in three planes at right angles to each other and in such case I employ three sets of parallel wires, the wires of each set being so positioned as to cut the ice in the three planes at right angles to each other.

In the accompanying two sheets of drawings I have illustrated an apparatus containing my invention in its simplest form.

30 In the drawings:

Figure 1 is a perspective elevation of the apparatus, showing in dotted lines a block of ice upon the point of bearing against the first sets of wires.

35 Fig. 2 is a plan view on a slightly larger scale of a corner of the apparatus.

Fig. 3 is an elevation of one of the frames for holding the cutting wires of the first and third sets, with the cutting wires in 40 position therein. Certain parts are broken away to show the parts behind them, as will be explained hereinafter.

Fig. 4 is a sectional view taken at right angles to Fig. 3, on the line 4, 4, the bolts 45 and rings being in elevation.

Fig. 5 shows the end of the frame illustrated in Fig. 3, which is preferred for holding the wires of the second sets.

50 Fig. 6 is a sectional view taken at right angles to Fig. 5.

Fig. 7 is a detail showing the terminal connection of the cutting wires and

Fig. 8 is a sectional elevation of the back wall of the apparatus showing an automatic switch for switching the electric current off of the wires 3 and onto the wires 6 and 8 automatically by the ice.

The machine illustrated is so constructed and tilted that the ice placed upon the receiving board slides by its own weight 55 against the first set of cutting wires and as it feeds through them by gravity, slips along and is guided by the second set which is not heated until the ice has passed entirely through the first set, whereupon the second 60 and third sets are subjected to the heating current and the ice then changes its direction and travels at right angles to its former course against the second set of wires and against the third set, which is immediately beyond the second, so that the two final 65 cuts are given and the cubes of ice drop into any receptacle suitable to receive them.

70 Referring to the figures.

1 represents the receiving board or chute 75 upon which the ice, 2, is placed preparatory to being dissected. The ice, being in place and the machine tilted, will press against the wires, 3, contained in the frame, 4, and as soon as the electric current is turned on 80 to those wires they will melt their way into it, the ice advancing by gravity into the space, 5, behind those wires. In so advancing it may be guided by the wires, 6, contained in the frame, 7, of the second set, or 85 it may be otherwise guided, as desired. When the ice has passed completely through the frame, 4, it is allowed to impinge on the wires, 6, which are then heated by the passage of a current and, the machine being 90 suitably tilted, the ice bears against them and they melt their way through the ice similarly to the first set. At the same time the wires, 8, of the third set contained in the frame, 9, are heated and the ice bears 95 against them and they also melt their way through the ice so that as it comes through the face of the machine it is dissected into small blocks or cubes which drop into a receptacle.

100 The frames 4, 7, and 9, may be secured in the apparatus in any convenient manner. I prefer to have them in slides similar to the slides for camera plates for convenience of

removal. But for simplicity in the drawings I have shown them in Fig. 1 and Fig. 2 as mounted upon bolts, 10, which will also serve to hold the parts 11 and 12, of the main frame together as shown in Fig. 1.

The method of securing the wires in the frames is as follows: At opposite sides of the frame I provide blocks, 13 and 14 shown in Figs. 3 and 4, of insulating material.

10 These blocks are of a general L shape and rest against shoulders, 15, in the side bars of the frame. The blocks are assembled in pairs and carry between them the supporting rings, 16, mounted in recesses, 17, formed in 15 the blocks.

The pair of blocks, 14, house between them, as shown in the tops of Figs. 3 and 4, the springs, 18, hung upon the bolts 19, the heads of which are seated in the edge of 20 frame 4. These springs being maintained in compression, and the end member of the frame together with its similarly formed cover plate, 20, providing guides within which the pair of insulating blocks may 25 slide, these blocks under the action of the springs will move away from the support of the shoulders, 15, whenever the wires expand under the heating effect of the current, and thus keep the wires taut and straight 30 under all conditions of expansion and contraction, the apparatus thereby producing blocks of ice of more perfect form.

The shoulders, 15, provide support for the blocks, 14, when the pressure of the ice on 35 the wires causes a stress greater than the springs are designed to resist.

The wires of each frame are in one continuous piece and at their ends are secured in sleeves, 21, by means of set screws, 22, shown 40 in Figs. 3 and 7. The sleeves are mounted in the insulators, 14, similar to the insulators, 13, and the ends of the wires are connected to the electric mains, *a* and *b*. The current enters through one of the terminals, *a* or *b*, 45 and passes through the wires and out at the other, and the wires are thus heated.

If the block of ice, after passing through the frame 4, is to be guided by the wires, 6, of the frame, 7, those wires must at their 50 receiving ends lie in the plane of the moving ice. Accordingly I carry the wires at that end by the support shown in Figs. 5 and 6. This support is virtually identical with that shown in Figs. 3 and 4, except that one of 55 the insulating blocks is omitted, the remaining one, 23, modified and the supporting ring changed to a disk, 24, held in place by a stud or rivet, 25.

The rings, 16, and disks, 24, I preferably 60 make of metal as it reduces the temperature in the wires at those points.

For convenience in mounting and demounting the wires I form the wire supporting sides of the frame of a rough L 65 shape as seen at 26 in Fig. 4, and I apply

cover plates, 20, and 27, which may be secured by bolts or screws, 28, or otherwise. In Fig. 3 I have shown these cover plates, 20 and 27, broken away to show the insulating blocks 13 and 14, behind them and I 70 have also shown the latter broken away at the left hand side of the figure to show the supporting rings, 16.

Fig. 5, which corresponds to Fig. 6, shows the wires thus passing under the disks, 24, 75 and then deflected by the edge of the insulating block, 13, into the plane of the moving ice.

While the electric currents may be controlled by hand switches if desired, I have 80 provided an automatic switch shown in Figs. 1 and 8, whose operation follows. 29 is a spring connected to one of the electric mains, as *b*. The free end of this spring is between two contacts, 30 and 31. The contact 30 85 connects with a terminal of wires, 3, the other terminal being connected to main *a*. The contact 31 connects with a terminal of wires 6 or 8, which are connected together in sets, the other terminal being connected to 90 main *a*. 32 is a pin projecting through wall 12 into the path of the advancing ice, 2, and adapted to act upon spring 29. The operation is this:—The ice, 2, coming through the wires, 3, comes against pin 32, when it is entirely through those wires and presses the pin, 32, and spring, 29, outward thus breaking the electric circuit at 30 and closing it at 31. The current thus ceases to pass through wires 3, which cool off, and passes 100 through wires 6 and 8, which are heated thereby and the ice then passes through the latter, as already described. 95

Having thus described my invention, and an embodiment of it, in the full, clear and exact terms required by law, and knowing that it comprises novel, useful and valuable improvements in the art to which it pertains, I here state that I do not wish to be limited to the precise construction and arrangement 110 of the several parts, as herein set forth, as the same may be variously modified by a skilled mechanic without departing from the spirit of the invention.

What I claim and desire to secure by Letters Patent of the United States is the following, to wit:—

1. An ice dissecting apparatus, comprising electrically heated wires, arranged in sets, and adapted by their heat to cut through 115 the ice in the desired directions, and automatic means for switching an electric current to each set alternately.

2. An ice dissecting apparatus, comprising in combination three sets of wires 120 angularly disposed upon removable frame, electrical connections supplying electric current to heat those wires, said sets being so positioned with respect to each other, and to the ice, as to cut it in three directions, 130

and automatic means to control said electric current.

3. An ice dissecting apparatus, comprising a tilted frame, provided with a slide 5 for receiving the ice, a set of electrically heated wires in the path of the ice, whereby it is cut on its passage from the slide through the wires, a second slide adapted to receive the ice as it leaves said wires and 10 tilted so that the ice tends to move at an angle to its former course, a second and third set of electrically heated wires at angles to each other arranged in the path of the ice as it moves in this new direction, 15 whereby it is cut into blocks by its passage through said last mentioned two sets of wires, and automatic means for switching the electric current alternately to each set.

4. In an ice dissecting apparatus, a wire holding frame comprising insulating blocks, arranged in pairs, and metallic supports 20 for the wires secured between each pair of blocks.

5. In an ice dissecting apparatus, three 25 sets of wires adapted to be heated electrically, means for automatically switching an electric current through each set of wires alternately, means for guiding a block of ice against the first set of wires and through 30 the same means for changing the direction of said ice and guiding it against the second set of wires, and means for guiding the ice, against the third set of wires, whereby the

ice is cut in three directions, forming square blocks.

6. In an ice dissecting apparatus, provided with a slide, a set of vertically disposed electrically heated wires, means for guiding a block of ice from said slide against and through said wires, one or more 40 other sets of wires also electrically heated, and disposed at right angles, and means for guiding the ice against and through said other sets of wires.

7. In an ice dissecting apparatus, provided with a slide, a set of vertically disposed electrically heated wires, means for guiding a block of ice from said slide against and through said wires, a second set of right-angle and vertically disposed wires 45 adapted to guide the ice as it issues from said first set of wires, means for automatically switching an electric current through said set of wires after the ice has passed through the first set, and means for guiding 50 said ice in its passage through the second set of wires.

In testimony that I claim the foregoing I have hereto set my hand in the presence of two witnesses, this 20th day of March, 60 1915.

GERMAIN POUCHAN.
